UNITED STATES PATENT OFFICE.

FERDINAND F. WAECHTER AND WILLIAM SCOTT CAMPBELL, OF PHILADELPHIA, PENNSYLVANIA, ASSIGNORS TO LINK-BELT COMPANY, OF CHICAGO, ILLINOIS, A CORPORATION OF ILLINOIS.

PIER STRUCTURE.

Application filed February 11, 1921. Serial No. 444,199.

To all whom it may concern:

Be it known, that we, FERDINAND F. WAECHTER and WILLIAM S. CAMPBELL, citizens of the United States, residing in Philadelphia, Pennsylvania, have invented certain Improvements in Pier Structures, of which the following is a specification.

Our invention relates to certain improvements in pier structures for loading vessels, either with cargo or with bunker coal.

One object of our invention is to reduce the cost of a structure of this type and to provide a movable hopper structure from which the coal is discharged, and to mount on the pier an overhead crane structure for carrying the telescopic chute, when such a chute is employed.

A further object of the invention is to design the crane structure so that cars, or other conveying mechanism, can be manipulated in the space under the span of the crane structure.

In the accompanying drawings:

Fig. 1 is a transverse sectional view of a pier illustrating our invention. On one side of the pier is a vessel being loaded with cargo coal and on the other side is a vessel being loaded with bunker coal;

Fig. 2 is a longitudinal sectional view of a portion of the pier structure;

Fig. 3 is a diagrammatic plan view of a pier, showing the tracks; and

Figs. 4 and 5 are detail views of the chute.

Referring to the drawings, 1 is a pier on which is mounted a series of structural frame 2 spaced a given distance apart and carrying an openwork structure 3, which extends substantially the full length of the pier. The structure consists, in the present instance, of a central frame 4, suitably braced, a base frame 5, and a heavier girder frame 6 carried by the central frame 4 and overhanging the central frame. On the girder frame 6 are rails 7 spaced a considerable distance apart and arranged to travel on the rails is a crane structure 8 in the form of an open span. On the girder frame 6, in the present instance, are three tracks. The two outer tracks 9 are the tracks for the loaded cars and the central track 9^a is the return track for the empty cars. At the outer end of the pier, the tracks 9 merge

into the track 9^a. At the land end of the pier the track 9^a merges into the tracks 9.

40 are elevators for raising the cars from 55 the tracks 41 to the level of the pier structure. 42 are car dumping tracks for discharging the cars into the specially constructed pier cars.

The above description relates to one arrangement of tracks, but the arrangement can be modified without departing from the main feature of the invention. Other means may be used for conveying material to the pier, if desired.

60 The crane structure is arranged to travel the full length of the pier. Mounted on the base of this structure 8 is a turn table 10, carrying a frame 11, which supports a boom 12, and the power house 13, in which 65 is located the mechanism which operates the boom and raises and lowers the telescopic chute which is suspended from the boom.

At each side of the base frame 5, in the 75 present instance, are hopper structures 16 mounted on trolleys 15 having wheels adapted to rails 14 on the frame 5. At the upper end of each hopper structure is an extension 43, which passes between guide 80 wheels 44 on the frame 6. 17 are hoppers, which are located in the upper portion of the hopper structure and are arranged to receive material through chutes 18 mounted on the frame 6. These chutes are arranged 85 directly under the rails 9 for the cars so that the cars can discharge their load directly onto the chutes and into the hoppers 17. At the side of each hopper structure 16 is a vertical channel 19 and the head end of the 90 adjustable chute 20 is located in this channel and can be raised and lowered by the ropes 21 leading to a drum 21^a, which may be turned either by hand or by power.

The chute 20 has a telescopic section 22, 95 which is operated by a motor 23, electrically controlled, in the present instance, and the chute has a guide roller 24 adapted to guides 25 on the chute 20. The shaft of the motor is connected to the shaft on which is 100 a worm 26, which is geared to the worm wheels 27 on shafts 28 adapted to bearings on the extension chute 22. On the lower shaft are pinions 29, which gear with racks

30 on the main chute, and on the upper shaft are wheels 31, which travel on tracks 32 on the main chute. By this means, when the motor shaft is turned in one direction 5 the extension chute will be projected, and, when the movements is reversed, it will be retracted.

The outer end of the chute is suspended by ropes 33, which pass around sheaves to 10 a drum 34, which may be turned by hand, or power, as desired. The chute 25, with its extension 22, discharges material into a telescopic chute 35, which is suspended by ropes 36 from the boom 12. The chute is 15 manipulated by power apparatus in the power house 13 carried by the structure 8 and the telescopic chute can be raised and collapsed so that it can assume the position shown by dotted lines in Fig. 1, clear of a 20 vessel, to allow the crane to be moved to either side of the pier, and can be lowered into a vessel, or extended, as shown in full lines.

When it is desired, the inclined chute 20 25 can discharge material directly into the hold of a vessel without using the telescopic chute, as shown at the right of Fig. 1. When the telescopic chute is raised, the boom can be moved so as to be directly above 30 the pier, which will allow a vessel to be brought to either side of the pier without the boom interfering with the rigging.

The means for operating the telescopic chute forms no part of the present invention, as it is set forth and claimed in an application for patent filed by William S. Campbell on the eighth day of February, 1921, Serial No. 443,386.

By the above construction, it will be seen 40 that a vessel can be loaded at either side of a pier and that the hopper structures can be moved into alignment with the hold of a vessel. When a telescopic chute is to be used, then the crane structure is traversed 45 to a point so that the boom will be above the hold of a vessel and the telescopic chute can be lowered into the hold, after which

the chute of the hopper structure is adjusted so as to feed material to the upper end of the chute.

By running loaded cars over one of the tracks 9, the cars can be discharged directly into the hopper and the material will flow down the inclined chute and into the telescopic chute from which it is discharged 55 by any suitable discharge mechanism at the base.

The cars, when unloaded, are run out to the end of the pier and returned on the tracks 9a.

We claim:

1. The combination of a pier; a main structure; longitudinal rails at one side of said structure; a hopper structure mounted on said rails so that it can be adjusted longitudinally on the main structure; a hopper and chute carried by the hopper structure; an overhead, pivoted crane having a boom; rails on the upper portion of the main structure on which the crane is mounted; and a 70 telescopic chute suspended from the boom of the crane and arranged to receive material from the hopper chute, the crane being pivoted so that the boom of the crane and the telescopic chute can be moved directly 75 above the pier.

2. The combination of a pier structure having longitudinal rails at each side; a hopper structure mounted on the rails at each side of the pier structure and arranged 80 to be moved longitudinally thereon; a hopper and chute on each hopper structure; a series of tracks on the pier structure; cars arranged to travel on said tracks; a rail at each side of the pier structure; a crane 85 structure; arranged to travel on the rails, said crane structure being in the form of an open span; a pivoted boom on said crane structure; and a telescopic chute suspended from the boom and arranged to be moved to 90 either side of the pier structure, or to be located directly above the pier structure.

FERDINAND F. WAECHTER.
WILLIAM SCOTT CAMPBELL.
